UNITED STATES PATENT OFFICE.

ALFRED JOHANNES SCHMIEDEL, OF DRESDEN, GERMANY, ASSIGNOR TO "UNIVERSALLE" CIGARETTENMASCHINEN-FABRIK J. C. MÜLLER & CO., OF DRESDEN, GERMANY.

DEVICE FOR CONTROLLING THE DRAW-OFF HOOK CARRIED BY THE FILLING MEMBER
IN CIGARETTE-FILLING MACHINES.

Application filed September 25, 1924, Serial No. 739,802, and in Germany January 11, 1924.

My invention relates to improvements in devices for controlling the draw-off hook carried by the filling member in cigarette filling machines.

5 In the ordinary cigarette filling machine a hook is employed for removing the completed and filled cigarettes from the beak or finger, and this is generally accomplished by a slide to which the hook is connected and which also 10 carries the plunger for feeding the cigarette cases to the beak, and it is necessary that the plunger and the hook move together in the longitudinal direction of the axis of the cigarette, and also move transversally.

15 The object of my invention is to provide means for longitudinally moving the slide and at the same time to impart the longitudinal and rocking movement to the beak or finger and also provide means whereby the 20 slide is held stationary when the beak or finger is operating on the completed cigarette.

Another object of my invention is to provide means whereby the movement of the plunger is in a definite relation to the movement 25 of the hook so that the same will be moved without shock, this being necessary due to the extraordinary rapidity with which the separate members follow one another in the ordinary cigarette machine.

30 A further object of my invention is to provide a simple, cheap and effective means for imparting this movement to the slide and simultaneously imparting the same movement to the hook and also imparting the 35 rocking movement to said hook.

In the accompanying drawings:—

Figure 1 is a side elevation of a cigarette machine showing my invention applied thereto.

40 Figure 2 is a view similar to Figure 1 showing the parts in different positions.

Referring now to the drawings, A represents the frame of the machine which is provided at its upper end with a slide *a* working in the guide-way *a'* and moving in a horizontal direction as clearly shown in the drawings. Carried by the slide *a* is a plunger *b* which pushes the cigarette cases out of the grooves *u* located in the periphery of the drum *T* onto the beak of finger *c*. Carried by the frame *A* is a horizontal shaft *d* driven in any desired manner and having secured thereon a cam disk *e*. On the inner face of

the cam disk *e*, adjacent the frame *A*, there is provided a cam groove adapted to receive 55 the horizontal outwardly extending pivot *g* carried by the lever *f*. The lever *f* is pivoted at its lower end at *h* to the frame *a* and its upper end is pivoted at *i* to the slide *a*, and thus it will be seen that as the cam revolves 60 the lever *f* will be reciprocated back and forth by the cam groove on the inner face of the cam *e* and cause a reciprocating movement to the slide *a*.

Pivottally mounted at *k* on the end of the 65 slide *a* is a double armed lever *n*. One arm *l* of the lever extends outwardly over the drum *T* and carries the hook *m* which may be adjusted thereon by means of the set screw *m'*. The other arm of the lever *n* has pivoted thereon at *o'* a rocking link *o* formed with a slot *p* extending in the direction of its length and in which slides the block *q* capable of turning upon the shaft *d*. The 70 rocking lever *o* has a pin *r* upon its inner face 75 which enters the closed cam groove *s* provided on the outer face of the cam disk *e* whereby the lever may be rocked by the cam groove as will be readily understood from the drawings. The cam groove *s* as shown 80 in Figures 1 and 2 of the drawings is formed with a portion *t* concentric with the shaft *d* for the purpose hereinafter more fully set forth.

Upon the rotation of the shaft *d* it will be 85 seen that the cam groove on the inner face of the cam *e* will move the lever *f* on its pivot *h* and thus move the slide *a* back and forth. The lever *n* is carried by the slide and will move back and forth with the slide. Due to 90 the fact that the lever *n* swings about the axis of the shaft *d* a longitudinal movement of the lever takes places as the pin *r* slides in the cam groove *s*. As soon as the portion *t* of the cam groove *s* moves in the path of the pin *r* upon the rotation of the cam disk *e*, the rocking lever is moved and the longitudinal movement of the lever by this portion of the groove imparts a rocking movement to the double arm *n* causing the hook *m* to be lowered to the beak *c* and upon the return movement of the slide *a* the completed cigarette 95 is withdrawn from the beak.

Having thus fully described my invention what I claim is:—

1. A cigarette machine comprising a ro-

- 5 tary drum having cross-wise slots in its periphery for the reception of cigarette cases, a finger or beak positioned at one end of the drum, a reciprocating slide carrying a plunger for pushing the cigarette cases into engagement with the said beak, a rotary member for imparting a reciprocating movement to said slide and plunger, a lever pivotally mounted on said slide, a hook connected 10 to one arm of said lever and adapted to reciprocate with the slide, and means connected to the other end of said lever and operated by the rotary member for causing the rocking of the lever to bring the hook into engagement 15 with the end of the cigarette while on said beak, and to raise said hook out of engagement with the cigarette after it has been removed from the slots in the rotary drum.
2. A cigarette machine comprising a rotary drum having cross-wise slots in its periphery for the reception of cigarette cases, a finger or beak positioned at one end of the drum, a reciprocating slide carrying a plunger for pushing the cigarette cases into 20 engagement with said beak or finger, a rotary member having a cam on one side for imparting a reciprocating movement to said slide and plunger, a lever pivotally mounted on said slide, means carried by said rotary member for imparting a rocking movement to the pivoted lever independent of the movement of the slide, and a hook carried by the lever and adapted to be brought into engagement 25 with one end of the cigarette while in place on said beak or finger and thus raise it out of engagement with the cigarette after it has been removed from the beak or finger.
3. A cigarette machine, including a rotary drum having cross-wise slots in its periphery 30 for cigarette cases, a finger or beak positioned at one end of the drum, a reciprocating slide carrying a plunger for pushing the cigarette cases into engagement with said beak or finger, a rotary driving shaft, a cam member 35 on said shaft having a cam on one side thereof for imparting a reciprocating movement to said slide and plunger, a lever pivotally mounted on said slide, a hook connected to one arm of said lever adapted to be reciprocated with the slide, a cam on the other side of said rotary member, a link on the other end of said lever having a sliding engagement with said drive shaft, a projection on said link in engagement with the last named cam 40 on said cam member to actuate the hook into engagement with the end of the cigarette while in place on said beak or finger and to raise it out of engagement with the cigarette after the cigarette has been removed there-

from on the reverse movement of the slide 60 and plunger.

4. In a cigarette machine including a rotary drum having cross-wise slots in its periphery for cigarette cases, a finger or beak positioned at one end of the drum, a reciprocating slide carrying a plunger for pushing the cigarette cases into engagement with said beak, a lever pivoted at one end to the slide and at its opposite end to the machine, a rotary member for imparting a reciprocating movement to the lever for moving the slide, a lever pivotally mounted on said slide, a hook connected to one arm of said lever and adapted to be reciprocated with said slide, means carried by the rotary member for engaging the opposite end of the lever to raise and lower the hook into and out of operative relation with the beak. 75

5. In a cigarette machine including a rotary drum having cross-wise slots in its periphery 80 for cigarette cases, a finger or beak positioned at one end of the drum, a reciprocating slide carrying a plunger for pushing the cigarette cases into engagement with said beak, a lever pivoted at one end to the slide, and at the other end to the machine, a rotary member having a cam groove for engaging the lever and imparting a reciprocating movement to the slide, a lever pivotally mounted on the slide, a hook carried by one arm of said lever, 90 means on the other end of said lever for engagement with a cam groove carried in the other face of the rotary member to raise and lower the hook.

6. In a cigarette machine, a rotary drum 95 having cross wise slots in its periphery for cigarette cases, a finger or beak positioned at one end of the drum, a reciprocating slide carried by the machine and having a plunger for pushing the cigarette cases into engagement with the said beak, a lever pivoted at one end to the frame and the opposite end pivoted to the slide, a pin carried by said lever, a rotary member carried by the machine and having a cam slot for receiving the pin for 100 imparting a reciprocating member to said slide, a bell crank lever pivotally mounted on said slide, a hook carried by one end of the bell crank lever, a link connected to the opposite end of the bell crank lever and pivotally mounted on the shaft of the rotary member, a pin carried by the link and operated in another cam groove in the rotary member for rocking the bell crank lever and raising and lowering the hook. 110

In testimony whereof I affix my signature.

ALFRED JOHANNES SCHMIEDEL.
